United States Patent Office.

J. H. ALDRICH, OF NASHUA, NEW HAMPSHIRE.

Letters Patent No. 70,384, dated November 5, 1867.

IMPROVED RAILROAD FREIGHT-CAR.

The Schedule referred to in these Letters Patent and making part of the same.

TO ALL WHOM IT MAY CONCERN:

Be it known that I, J. H. ALDRICH, of Nashua, county of Hillsboro, in the State of New Hampshire, have invented a new and useful Improvement in Railroad Freight-Cars. The following is a correct description thereof, reference being had to the accompanying drawings, and letters marked thereon, making a part of this specification.

My invention consists in constructing the car with oblong apartments, of a given height, and a chamber or room in the top part, which is for the safety and economy of transporting live stock. I will describe it by referring to the accompanying drawings.

Figure 1 is a side elevation.

Figure 2 is a sectional view.

Figure 3 a top view.

In fig. 1, letters A A are doors, with duplicates in the opposite side of the car. In fig. 2, letters B B are apartments, extending across the car from side to side. By this arrangement each creature is secured in its respective place without being tied, and in such a manner that a single one may be loaded or unloaded at either side of the car without interfering with the others. Letters C C are chambers or rooms, in which food or subsistence for the stock may be carried when on transportation. In fig. 3, letters D D are doors, which open into said chambers C C, and form part of the top covering of the car.

As it is not safe to tie cattle by the neck when on transportation, in case of accident or sudden motion of the car, I therefore disclaim all such arrangements.

What I do claim as my invention, and desire to secure by Letters Patent, is—

The cattle-car, when substantially arranged as and for the purpose described.
